CLAIM

The ornamental design for a pipette tip storage assembly, as shown and described.

DESCRIPTION

FIG. 1 is a top perspective view of a pipette tip storage assembly.

FIG. 2 is a top partially exploded perspective view thereof;

FIG. 3 is a top exploded perspective view thereof;

FIG. 4 is a bottom perspective view thereof;

FIG. 5 is a front view thereof;

FIG. 6 is a rear view thereof;

FIG. 7 is a left-side view thereof;

FIG. 8 is a right-side view thereof;

FIG. 9 is a top view thereof; and,

FIG. 10 is a bottom view thereof.

The broken lines depict portions of the pipette tip storage assembly that form no part of the claimed design.
